COMBINED INCUBATOR AND ILLUMINATOR FOR TEST TUBES AND RACK FOR PIPETTES

Gerald D. Gulotta and George Goda, New York, N.Y.,
assignors to Clay-Adams, Inc., New York, N.Y., a cor-
poration of New York

Filed Jan. 22, 1962, Ser. No. 68,388

Term of patent 14 years

(Cl. D16—2)

FIG. 1

FIG. 2

FIG. 3

FIG. 4

FIG. 5

FIG. 1 is a perspective view of a combined incubator and illuminator for test tubes and rack for pipettes showing my new design.

FIG. 2 is a side elevational view thereof looking from the left of FIG. 1;

FIG. 3 is a side elevational view thereof looking from the right of FIG. 1;

FIG. 4 is a bottom plan view thereof; and

FIG. 5 is a rear elevational view thereof.

The top inner portion of the front inclined panel not disclosed in FIGS. 1, 2 and 3 is substantially flat and unornamented.

We claim:

The ornamental design for combined incubator and illuminator for test tubes and rack for pipettes, as shown and described.
